UNITED STATES PATENT OFFICE.

GILBERT C. HODGES AND WILLIAM M. LOHNEs, OF SARATOGA SPRINGS, NEW YORK.

DUMP-WAGON.

1,242,805.

Specification of Letters Patent.

Patented Oct. 9, 1917.

Application filed February 8, 1916. Serial No. 76,979.

To all whom it may concern:

Be it known that we, GILBERT C. HODGES and WILLIAM M. LOHNEs, citizens of the United States, residing at Saratoga Springs, 5 in the county of Saratoga and State of New York, have invented new and useful Improvements in Dump-Wagons, of which the following is a specification.

This invention relates to dump wagons of 10 that class which are provided with hinged bottom doors in contradistinction to that type of dump wagons from which the load is discharged by tilting the body of the wagon.

15 Manufacturers and users of dump bottom wagons have been confronted with a difficulty resulting from the insufficient clearance between the doors and the surface of the ground when the doors are in dumping position, such clearance, in standard wagons, rarely exceeding twelve inches. The result has been that when the load is dumped it would obstruct the doors, thereby obstructing the free movement of the wagon either 20 in turning or in advancing, and also obviously obstructing the closing of the doors until the wagon would be moved to a distance from the heap or pile formed by the load just deposited on the ground. The 25 wrenching and straining caused by the effort to move the wagon would also obviously be detrimental to the wagon structure and would operate to shorten the life thereof.

The present invention has for its prime 30 object to produce a bottom dump wagon in which the doors will be capable of moving to such a position as to produce an ample clearance when the load is discharged.

A further object of the invention is to 35 produce means whereby the doors after swinging open will be moved to a non-obstructing position with respect to the load just deposited on the ground.

40 A further object of the invention is to produce means for moving the doors to a non-obstructing position which will not interfere with the arrangement and operation of the means customarily employed for opening and closing the doors.

45 A further object of the invention is to provide for the use, in a device of the class described, of springs whereby the doors after being permitted to swing open will be moved to a "clearing" position without 50 special effort on the part of the operator.

With these and other ends in view which will readily appear as the nature of the invention is better understood, the same consists in the novel construction, arrangement and combination of parts which will be hereinafter fully described and particularly 60 pointed out in the claims.

In the accompanying drawings has been illustrated a simple and preferred form of the invention, it being, however, understood 65 that no limitation is necessarily made to the precise structural details therein exhibited, but that changes, alterations and modifications within the scope of the claims may be resorted to when desired.

70 In the drawings,—

Figure 1 is a top plan view of a dump wagon to which the invention has been applied.

Fig. 2 is a side elevation of the same.

Fig. 3 is a rear elevation.

Fig. 4 is a detail view of the winding drum and related parts.

Corresponding parts in the several figures are denoted by like characters of reference. 80

The invention has been shown applied to an ordinary dump wagon of which A designates the body, B and C, the rear and front axles, respectively, D, the neck, E, the seat, and F, the doors which are adapted to be 85 operated by chains G connected with or guided over a pulley H known as an equalizer, said chains being also connected with a drum I, whereby they may be released or tensioned to open and close the doors. 90

Under the present invention the doors are provided with straps 15 having terminal loops 16 engaging vertically disposed guide rods 17 which are fixed externally on the side walls of the wagon box, said guide rods 95 being substantially vertical and parallel to each other. The loops 16 are adjacent to the outer side edges of the bottom side members, and they coöperate with the guide rods 17 to form hinges that will permit the doors to swing beneath the wagon box when said doors are positioned with the loops 16 adjacent to the lower ends of the guide rods. Pulleys 18 are journaled near the upper ends 100 of the respective guide rods 17 on shafts 18' which extend in engagement with the guide rods 17, the pulleys 18 being disposed intermediate the said guide rods and a wagon body. Flexible elements such as chains 19 are connected with some of the 105

110

loops 16, said chains being guided on the pulleys 18 and joined together so as to form at each side of the wagon body a single pulling chain 20.

- 5 At each side of the wagon, near the front end thereof, is mounted a strong coiled spring 22 with which the pulling chain 20 at the corresponding side of the wagon is connected. Each of said springs is also
10 connected by a chain 23 with a winding drum 21 on which the said chains 23 are adapted to be wound. Fulcrumed on the winding drum is a hand lever 24 having a pawl 25 engaging a ratchet wheel 26 on the
15 winding drum, said ratchet wheel being also engaged by a dog 27 whereby it may be locked against reverse rotation.

When the doors are closed, the springs 22 will be tensioned and the chains 23 will be
20 wound on the drum shaft 21. When the doors are permitted to swing to a load discharging position, and the drum shaft 21 is released, it will be rotated by the contractile action of the springs 22, thereby unwinding
25 the chains 23, the chains 20 being at the same time pulled or tensioned by the action of the springs sufficiently to lift the doors bodily to the position shown in Fig. 2. By properly proportioning the parts the doors
30 may be elevated until they are clear of the bottom edges of the side walls of the wagon box, thereby providing for the maximum amount of clearance. The extent to which the doors may be lifted may, however, be
35 varied. By rotating the drum shaft 21 by means of the hand lever 24 the springs 22 may be tensioned, and the doors will be gravitationally lowered until they may be swung to their usual closed position by the
40 means provided for the purpose.

Copies of this patent may be obtained for five cents each, by addressing the "Commissioner of Patents, Washington, D. C."

Having thus described the invention, what is claimed as new, is:—

1. A wagon body, vertical guide rods secured on the outer faces of the side members thereof, guide pulleys positioned intermediate the rods and the wagon body, door members having straps provided with terminal loops engaging the guide rods, and chains connected with the loops guided over the pulleys and joined together to form at each side of the wagon body a single pulling chain, in combination with springs with which said pulling chains are connected to bodily lift the door members adjacent to the outer faces of the sides of the wagon body. 50

2. A wagon body, vertical guide rods secured on the outer faces of the side members thereof, guide pulleys positioned intermediate the rods and the wagon body, door members having straps provided with terminal loops engaging the guide rods, and chains connected with the loops guided over the pulleys and joined together to form at each side of the wagon body a single pulling chain, in combination with springs with 55 which said pulling chains are connected to bodily lift the door members adjacent to the outer faces of the sides of the wagon body, and a winding drum, means for rotating the same, and chains connecting said drum with 60 the springs for the purpose of tensioning the same.

In testimony whereof we affix our signatures in presence of two witnesses.

GILBERT C. HODGES.
WILLIAM M. LOHNES.
